(57) **CLAIM**

The ornamental design for a translucent product holding shelf with inclusions, as shown and described.

DESCRIPTION

A description of the appearance of the article is as follows: FIG. 1 is a perspective view of a translucent shelf showing my new design.

FIG. 2 is a front elevational view thereof, the rear elevational view being a mirror image thereof.

FIG. 3 is a top plan view thereof, the bottom plan view being a mirror image thereof; and,

FIG. 4 is a cross-sectional view taken along line 4—4 of FIG. 3 showing the inclusions embedded in the translucent shelf structure thereof.

A description of the appearance of the article is as follows: A product holding shelf for use in holding and merchandising products therefrom made of a translucent material wherein the translucent material includes a plurality of inclusions embedded within the material which can be seen and viewed through the translucent material. The translucent material may be of any color so long as the inclusions may be viewed therethrough.

The broken lines shown are for illustrative purposes only and form no part of the claimed design.
